VIBRATING TOOTH BRUSH

William F. Sticht, Maplewood, N. J.

Application April 22, 1932, Serial No. 606,770

10 Claims. (Cl. 128—55)

This invention has reference to what are known as vibrating tooth brushes, in which means are provided for effecting rapid impacts on the portion of the tooth brush that directly engages the teeth or gums of the user, that will have a message effect on the gums.

One object of the invention is to provide an improved device of this character in which the impacts will be imparted to the brush member directly, and not to the end portion of the device, that is likely to come into contact with the teeth.

A further object of the invention is to provide an improved mounting of the brush member to cause its vibratory action.

15 A further object of the invention is to provide improved means for imparting the reciprocations of a core of magnetizable material a solenoid magnet to the impact member of the device.

Another object of the invention is to provide 20 improved means for preventing moisture or water from the brush member from entering into the solenoid and core, which might cause a short circuit.

Another object is to provide an improved form 25 of bristle member arranged to pass into the gum portions between the teeth.

In the accompanying drawings are shown embodiments of my invention:

Figure 1 is a bottom elevation.

30 Fig. 2 is a longitudinal section, partly in elevation.

Fig. 3 is a section enlarged on the line 3—3 of Fig. 2.

Fig. 4 shows a detail of the locking joint for 35 the brush member.

Fig. 5 is a cross section enlarged on the line 5—5 of Fig. 2.

Fig. 6 is a cross section enlarged on the line 40 6—6 of Fig. 2.

Fig. 7 is a longitudinal section enlarged of one end portion.

Fig. 8 shows some of the parts of Fig. 7 in another position.

Fig. 9 shows the rubber washer.

45 Fig. 10 is a longitudinal section enlarged at the rear end.

Fig. 11 is a cross section on the line 11—11 of Fig. 10.

Fig. 12 shows the brush member detached.

50 Fig. 13 shows another form of tooth engaging member.

As shown in the drawings the device comprises a handle portion, in the form of a casing 2, and a brush member, or brush holding member in the form of a tubular shank or sleeve 3. The handle

casing 2 has a solenoid or magnet 4 mounted therein, and arranged to slide a short distance, being pressed outwardly at its inner end by a coil spring 5, that engages a shoulder 6 of the casing 2, and also the inner end of the solenoid, while the outer end of the solenoid is thus pressed against a head 7 of electric insulating material that is screw-threaded to engage the internal threads of the casing to have adjustment into and out of the casing and adjust the position 10 of the solenoid in the casing, see Fig. 10. The head 7 has a bore 8 to receive wires 9 and 10, that connect with insulated screws 11 and 12, from which terminals 13 and 14 lead to the extremities of the solenoid winding.

15 In the bore 15 of the solenoid slides a plunger bar of magnetic material 16, that is rigidly connected with a stem 17 of non-conducting material having a reduced extension 18. This extension will abut a brush stem 19 carried by the 20 sleeve 3, and the reciprocation of the bar 16 will cause impacts of the extension 18 upon the stem 19. The sleeve or shank 3 is arranged with a hood 20 at the end opening through one side to receive the bristle member, or other member for 25 engaging the teeth or gums. In the tubular portion of the shank near this opening is secured a plate spring 21 by its bent end 22, which spring at its other end is bent around the transversely connecting part 23 of the legs 24 of a yoke or 30 U-shaped link member.

Each of the link legs 24 is connected pivotally at the end to the side walls of the hood, as at 25. The connecting portion of the link legs 24 is bent laterally, as at 26, see Fig. 3. The outer end of 35 the plate spring 21 is bent to form a loop 27 through which projects the transverse leg connecting part 23. This transverse part 23 on each side of the spring loop pivotally carries short links 28 and 29, the lower ends of which carry 40 a pivot pin 30. The stem 19 of the brush member at its outer end has a cross bore to receive the pivot 30, and between this pivot connection of the stem and each link is a roller, 31 and 32. These rollers normally lie at the bottom of an 45 inclined end wall 33 of the hood. It will be seen that longitudinal movement of the stem 19 imparted thereto by the extension of the magnet core 16 will advance the short links, and they will exert an upward force on the link 23, 24 which 50 will flex the outer end of the plate spring 21 outwardly toward the hood opening and, at the same time these rollers will ride up the inclined wall 33 and thereby move the outer end of the link 23, 24 laterally toward the hood opening. When the 55

thrust on the stem 19 is removed the spring 21 will return the parts to normal position.

The plate spring 21, and also the long links serve to carry the brush member, comprising a back 34 and bristles 35. The back is provided on each side with a groove 36 by which it can slide in on the long links 24, being cut away at 37, which portion 37 passes beyond the downward bend of these links. This swinging movement of the long links and plate spring will be imparted to the brush member from the impacts of the solenoid core.

The plunger bar 16 will be caused to reciprocate by the fluctuation of the current in the magnet, and between this plunger bar and the stem 17 is an annular recess, thus forming opposite stop walls 38 and 39. In this groove is placed a washer 40, the stop walls being further apart than the thickness of the washer to permit it to slide to alternately engage these walls. The stem 17 is provided with lugs 41 (see Fig. 8) on several places, that engage one end of a coil spring 42, whose other end presses against the washer 40 to normally hold the washer in engagement with the stop wall 38. When the plunger bar 16 is drawn inwardly it will press the washer 40 against the end wall 43 of the magnet, see Fig. 8. An annular stop ring or wall 44 is arranged in the casing 2, opposite the outer portion of the washer 40 to permit slight movement of the washer away from the magnet wall 43, but it will be seen that the movement of the washer between the walls 43 and 44 is somewhat less than the movement of the washer between the core wall 38 and the opposite wall 39.

It will be further seen that the shank 3 of the brush member is detachably mounted in the casing 2. The latter casing is preferably of a molded material, such as bakelite, with a reduced portion 45 to receive a sleeve 46 threaded thereon. This sleeve has a reduced extension 47, with a shoulder at 49, that receives a disc 72, surrounding the stem extension 18 on its inner portion. This disc serves to combine and compress a series of washers 50 of resilient material, such as rubber, see Fig. 9. Four of these are shown, having their outer portions pressed against a shoulder 48 of the casing 2. Each of these washers comprises an outer ring portion 51, an inner ring portion 52, which portions are connected integral by a web portion 53, the latter being curved or flexed in, to readily permit the movement of the inner portion of the washers, on the stem, or with the stem.

It will be seen that the enlarged inner end 54 of the shank 3 will slide into the extension 47 of the sleeve 46, and this portion 54 is preferably split and has a bayonet slot 55, that engages a pin 56 on the sleeve 46 to lock the brush member, and permit its removal. The stem 19 in this shank passes through a ring 57 of soft material such as cork. This is carried by an eyelet member 58 which engages the bore of the cork ring and is flared on the opposite face of the cork ring against a washer 59, see Fig. 7. The inner end 54 of the shank is pressed inwardly in several places at 60 to hold the cork in place. The outer end of the sleeve portion 47 is screw-threaded to receive an internally threaded ring 62, having an internal bevelled extremity 63 of the sleeve portion 47. This ring will be screwed up after the shank end 54 has been inserted into the sleeve extension 47 and connected thereto by the bayonet joint to make a tight fit. It will be further seen that the extremity of the split tubular portion 54 is flared inwardly to engage the

bevelled portion of a disk 72 held between the sleeve 47 and the end of the casing 2. When this split sleeve is compressed by the ring 62 these bevelled portions will tightly engage and hold the sleeve in position. It will be further understood that the stem 17 secured to the plunger 16 is formed of suitable insulating material, such as bakelite, that will prevent any possible leak of the current from the solenoid and adjacent parts that might pass into the stem 19.

In Fig. 13 I show another form of brush member, which is formed of soft rubber, comprising a back plate 64 with a series of plates 65 extending laterally from and transversely of the back, and spaced a short distance apart. These latter plates as shown are of arcuate form with the marginal portions serrated, as at 66, and the side walls 67 may be provided with radial corrugations.

In Fig. 12 the bristle tufts 35 are shown specially arranged, in transverse rows of three each, the middle tuft 71 standing upright with the end bevelled off toward each side. The tufts of each outer row are set in sockets 68 and 69 that are inclined so that these tufts 70 and 71 lean toward the middle tuft, and their end portions are bevelled or inclined toward the middle tuft as shown.

The plunger bar 16 is drawn inwardly by the magnetic forces generated by the solenoid, and also by the fixed core 73 of the solenoid, and this may act as a stop to limit the inward movement of the plunger as indicated in Fig. 8. It will be seen that the parts lie normally as indicated in Fig. 2 with the coil spring 42 pressing the washer 40 against the stop wall 38 of the plunger 16, but this washer 40 now engages the outer stop 44, and the plunger is spaced from the core 73. When the solenoid is energized, the plunger 16 will be drawn inwardly, and the washer 40 will be brought against the end wall 43 of the solenoid, see Fig. 8. On change of the current or reversal, the plunger 16 being released, the coil spring 42 that was tensioned on the inward movement of the plunger and stem 19, will now be free to move the stem 19 outwardly, and as soon as the wall 38 of the plunger strikes the washer 40, the tension of the spring will be relieved and it would not by itself carry the plunger and stem further outward, but travel or momentum of these parts will advance the stem 19 and rod 19 further outward, causing the washer 40 to travel from the position of Fig. 2 until it strikes the ring 44 that will limit this movement, see Fig. 7.

It will be understood that these outward movements of the rod 19 from the position of Fig. 2 to that of Fig. 7, will swing the brush carrier and the brush, and that impact results from the end of the stem 18 engaging the end of the rod 19.

The plate spring 21, will swing at its outer end by the link connection and carry the brush with it, and this tension of the spring when relieved will move the stem rod 19 and the links back to their normal position of Fig. 2. This spring is given a kind of loop or bend 75 that will assist in retaining the brush block 69 in engagement with the long links, but permit its ready removal.

What I claim is:

1. In a vibrating toothbrush, a chambered handle, a tubular shank connected at one end to and extending from one end of the handle and arranged with a hood at the opposite end with the opening of the hood at the side of the shank and the outer wall of the hood inclining toward the hood opening, a magnetic vibrator longitudinally 75

reciprocatory in the handle chamber, a stem mounted in the shank to have longitudinal movement, with the inner end abutting the vibrator and adapted to be moved longitudinally outward by the vibrator, a bearing carried at the outer end of the stem engaging the inclining end wall of the hood, a pair of links each connected at one end to the outer end of the stem, a U-shaped link connected to the opposite end of each of said links and each leg of said U-shaped link extending rearwardly and pivotally connected at its end to a wall of the hood, a plate spring connected at one end to the U-shaped link at the pivot connection thereof with the pair of links and secured at the opposite end to the shank at the rear of the hood and urging the stem longitudinally in a direction toward the vibrator, and a brush detachably held between the legs of the U-shaped link to extend outwardly from the hood opening, the parts being arranged whereby movement transmitted to the stem by the vibrator will cause the end of the stem to ride up the inclining wall of the hood and move the brush in a direction outward from the hood opening and place the spring under flexure, and said spring plate imparting retracting movement to the brush and stem.

2. In a vibrating toothbrush, a brush, a chambered handle, a tubular shank connected at one end to and extending from an end of the handle and arranged with a hood at the outer end with the opening of the hood at the side of the shank and the outer end wall of the hood inclining toward the hood opening, a magnetic vibrator longitudinally reciprocatory in the handle chamber including a stem extending into the shank, a second stem longitudinally slideable in the shank with the inner end abutting the vibrator stem and adapted to be moved longitudinally in one direction by the vibrator and the outer end of said second stem having a bearing on the inclining wall of the hood, and resilient means to support the brush in the hood opening said resilient means connected with the second stem to transmit return movement to and maintain the inner end of the second stem in abutting relation to the vibrator stem.

3. A vibratory brush as claimed in claim 2, wherein the resilient brush supporting means comprises a spring plate having a link connection at one end with the end of the second stem bearing on the inclining wall of the hood and secured at the opposite end to the shank rearward of the hood opening, and means juxtaposed to the side walls of the hood pivotally connected to the link connection of the spring plate with the second stem and to the side walls of the hood rearward of the hood opening and adapted to engage grooves in the respective sides of the brush.

4. In a vibratory tooth brush, a tubular casting with a closure secured to one end and having a bore therethrough, a solenoid in the casing arranged with means for the connection of electric conductors extended through the closure bore, a plunger of magnetizable material slideable in the solenoid, a stem of non-conducting material connected to the plunger to participate in the movements thereof and adapted for connection of a work member, means to yieldingly urge the stem with the plunger in one direction and the plunger and stem adapted to be moved in the opposite direction against the force of said yielding means under the influence of the magnetic force generated by the solenoid, means for limiting the movement of the plunger and stem,

and means through which the stem is extended, said means being releasibly secured in a recess in the end of the casing opposite the closure and engaging the recess wall to permit of reciprocatory sliding movement of the stem with the plunger and provide a liquid tight seal between the stem and the casing.

5. A vibrating tooth brush as claimed in claim 4, wherein the means to provide a liquid tight seal between the stem and the casing comprises a series of juxtaposed rubber washers seated against a shoulder in the end of the casing with the peripheral wall and the washers engaging the casing wall and the washers engaged on a reduced portion of the stem with the wall of the washer openings engaging said reduced portion of the stem, a sleeve threaded onto the end of the casing, and a disk interposed between said sleeve and casing compressing the peripheral portion of the rubber washers between said sleeve and the casing shoulder.

6. In a vibratory tooth brush, a tubular handle with a closure adjustably secured in one end and having a bore therethrough, a solenoid in the handle adapted for connection of electric conductors extended through the closure bore, means in the casing to urge the solenoid to the end closure, a stem of non-conducting material mounted in the handle at the end of the solenoid opposite the closure to have sliding movement and held against rotation and adapted for connection of a work member, a bar of magnetizable material slideable in the solenoid and connected to said stem, a spring to urge the stem and bar outward from the solenoid, and said bar and stem adapted to be moved against the force of said spring under the influence of the magnetic forces generated by the solenoid, means to provide a liquid tight seal between the stem and the handle, and means to limit the movement of the stem and bar outward from the solenoid.

7. A vibrating tooth brush as claimed in claim 6, wherein the bar has a reduced portion extended into and whereby it is connected with the stem, with the end of the stem in spaced relation to the shoulder formed by the reduced portion of the bar, and the means to limit the outward movement of the stem and bar comprises a washer having a peripheral portion offset axially and engaging the end of the solenoid with the portion at the opening spaced from the solenoid, and a second washer engaging the shoulder formed by the reduced portion of the bar with the peripheral portion engaging in the space between the solenoid and the first washer.

8. In a vibratory tooth brush, a tubular handle having a removable closure at one end, magnetic vibrating means in the handle, said vibrating means including a solenoid adapted for connection with a source of electric current and a bar of magnetizable material slideable in the core of the solenoid, a stem extended through the end of the handle opposite the closure, and connected to the bar, means normally urging the stem and bar in a direction outward from the solenoid and said stem and bar adapted to be moved toward the solenoid against the force urging the stem and bar outward from the solenoid under the influence of the magnetic forces generated by the solenoid, means to limit the outward movement of said stem and bar, means to provide a liquid tight seal between the extended end of the stem and the handle, a tubular shank, a brush holder carried by the shank, a second stem slideable in the shank, means to connect the brush

holder with the latter stem to transmit the longitudinal movement of said stem to movements of the brush holder laterally of the stem, means to urge the brush holder to a predetermined position and the connected stem in one direction, and means to releasably connect the shank to the handle and operatively connect the second stem with the first stem to transmit the movement of the latter stem in one direction to the second stem and transmit said movement of the stems to lateral movement of the brush holder.

9. A vibrating tooth brush as claimed in claim 8, wherein the means to releasably connect the shank with the handle comprises a sleeve having two diameters, the part of larger diameter having screw threaded connection with the handle with a washer interposed between the shoulder formed by the reduced portion and the end of the casing, said washer having a centrally depressed portion the wall of which inclines to the axis of the washer, the shank being adapted to be engaged in the portion of the sleeve of smaller diameter with the end abutting the inclined wall of the washer to exert an outward force on the end of the shank, and a ring threaded onto the sleeve, said ring having a beveled portion to cooperate with a beveled end of the sleeve to clamp the sleeve to the shank.

10. In a vibrating toothbrush, a chambered

handle, a tubular shank connected at one end to and extending from an end of the handle and arranged with a hood at the outer end with the opening of the hood at the side of the shank and the end wall of the hood inclining toward the opening, a magnetic vibrator longitudinally reciprocatory in the handle chamber including a stem extending from the handle chamber into the shank, a second stem longitudinally slidable in the shank with the inner end abutting the 10 vibrator stem and having an anti-friction bearing at the outer end on the inclining wall of the hood, a brush having grooves in and extending longitudinally of the respective sides of the back thereof, a spring plate secured at one end to the 15 shank at the rear end of the hood opening and extending longitudinally of said opening, a U-shaped member connected at the portion intermediate the legs thereof to the spring plate and pivotally supported at the ends of the legs by the 20 side wall and at the rear end of the hood to extend longitudinally of and in spaced relation to the spring plate and adapted to engage the grooves in the sides of the brush back, and links connecting the U-shaped member at the connection thereof with the spring plate to the end of the second stem.

WILLIAM F. STICHT.
